UNITED STATES PATENT OFFICE

2,346,235

MULTIDIRECTIONAL ELECTRIC
DRY SHAVER

August Romao, San Francisco, Calif.

Application July 21, 1941, Serial No. 403,356

11 Claims. (Cl. 30—43)

My invention relates to improvements in a multi-directional electric dry shaver, and it consists of the combinations, constructions and arrangements hereinafter described and claimed.

An object of my invention is to provide a multi-directional electric dry shaver that has a guard with circular hair-receiving openings with cutting edges around their entire circumferences, and a cutter reciprocably and rockably mounted in the guard and having cutting edges extending at different angles to each other so that when the cutter is moved through a double helical motion, its cutting edges will cooperate with the entire circular cutting edges for severing all of the hair received in the guard openings. The round holes constitute shearing edges that will actually and effectively shear hair on every direction of their circumferences.

A further object of my invention is to provide a device of the type described in which the guard has two groups of laterally extending slots arranged on opposite sides of the group of circular openings. The slots are for the purpose of receiving longer hairs and comb-like members are associated with the slots and are used for the purpose of combing the longer hairs and for guiding them into the slots where they will be severed by the cutter. The comb-like members provide multiple hair-parting combs of novel construction which not only guide the hairs into the slots, but cause the hairs to remain between the shearing edges of the slots until sheared by the cutter. Such a multiple hair-parting comb also reduces skin irritation to a minimum.

A still further object of my invention is to provide a device of the type described in which the circular cutter is yieldingly and constantly kept in contact with the perforated portion of the guard by spring-pressed pins that exert radial forces against the cutter from different angular directions.

Other objects and advantages will appear in the following specification, and the novel features of the device will be particularly pointed out in the appended claims.

My invention is illustrated in the accompanying drawing forming a part of this application, in which:

Figure 1 is a longitudinal section through the device shown twice normal size;

Figure 2 is an end elevation of the device on the same scale;

Figure 3 is a transverse section of Figure 1, taken along the line III—III of Figure 1 and illustrating the parts at four times normal size;

Figure 4 is a plan view (eight times normal size) of a portion of the cutter and guard; and

Figure 5 is a schematic view illustrating four positions of the cutter with respect to a circular hair-receiving opening.

While I have shown only the preferred form of my invention, it should be understood that various changes or modifications may be made within the scope of the appended claims without departing from the spirit of the invention.

In carrying out my invention, I provide an electric dry shaver casing indicated generally at A in Figures 1, 2 and 3. The casing houses an electric motor, not shown, and the motor shaft 1, which is rotated by the motor, has an eccentric portion or stem 2 with a roller 3 that has a spherical periphery. The casing A has a guard-receiving recess A' therein and an opening 4 communicating with the recess through which the shaft 1 extends.

A guard indicated generally at B has a rectangular base that is removably received in the recess A'. A set screw 5 or other suitable fastening means is used for securing the guard to the casing. It is best now to describe the guard in detail after which the cutter C will also be set forth in detail. The top of the guard is semi-cylindrical and it has a cylindrical bore 6 disposed so close to the semi-cylindrical top as to provide a metal thickness at its narrowest point of about three one thousandths of an inch in thickness.

The thin guard portion thus provided has a plurality of circular hair-receiving openings 7 therein. These openings are preferably twenty five one thousandths of an inch in diameter although I do not wish to be confined to this exact measurement. The openings are arranged in a plurality of rows and I have indicated three rows in Figure 4. The openings in adjacent rows are staggered and they are placed as close together as possible. This construction does not weaken the perforated guard portion to too great an extent since the differences in curvatures between the outer cylindrical surface of the guard and the inner cylindrical surface of the bore 6 is such as to provide metal adjacent to the sides of the group of circular openings which will rapidly increase in thickness. The guard portion

that has the circular openings can be thin because the metal around each opening forms a continuous reinforcement around the opening that serves to support the entire area against external pressure. This external pressure is caused by placing the guard against the skin in

45

50

55

the act of shaving. The entire circular edge of each opening 7 constitutes a hair cutting edge as will be hereinafter described more fully.

In addition to the circular openings 7, I provide two groups D and E of transversely extending slots 8. The slots in each group have their inner ends preferably extending from points near to the circular openings 7. In actual practice, ten thousandths of an inch separates the openings from the slots. The other ends of the slots terminate at points making angles of 90° with a median line extending longitudinally through the center row of openings 7. The slots 8 are preferably ten thousandths of an inch in width and the distance between adjacent slots is preferably fifteen thousandths of an inch in width. The inner edges 8a of the slots constitute cutting edges and also the parallel edges 8b of the slots constitute hair-cutting edges. The thickness of the guard metal wall between the circular openings 7 and the inner ends of the slots 8 is preferably five thousandths of an inch in thickness. As already stated, the thickness of the curved top of the guard wall rapidly increases from an extreme thinness of about three thousandths of an inch at the top of the guard due to the difference in curvature between the outer guard surface and the bore 6. A wedge-like supporting construction is thus provided for both guard wall portions that extends from the circular openings 7 to the guard base.

The circular openings 7 are designed to receive short hairs while the slots 8 are adapted to receive longer hairs. I provide novel means for guiding the longer hairs into the slots 8 and this comprises comb-like portions 9 arranged between adjacent slots. The slots 8 define bars 10 and these bars have outwardly extending projections 9a that form the multiple hair-parting combs 9. The overall height of the projections is preferably not over one thirty second of an inch and the projections in each comb are placed as close together as possible. The projections taper to their outer ends which are rounded points so as to reduce skin irritation to a minimum. The comb teeth are placed close together so as to travel over the skin with less tendency to dig into the skin, thus avoiding this type of discomfort to the user. The inner comb ends start at an angle of approximately twenty two and one half degrees from each side of the median line that extends through the central row of circular openings 7, and the outer comb ends terminate at about an angle of forty five degrees. The multiple combs 9 in bordering the sides of all of the slots 8 will immediately part the longer hairs and guide them into the slots and cause them to remain within the shearing edges of the slots until sheared off by the cutter. The multiple combs prevent the longer hairs from emerging from the slots due to the action of each tooth being followed by a succeeding one to hold the hairs in the slots until sheared.

It is best now to describe the cutter C. The cutter has an outer cylindrical diameter the same as the diameter of the bore 6 except that the bore 6 is large enough to permit a slight clearance between the bottom of the cutter and the bottom of the bore. The length of the cutter is less than the length of the guard so that during the reciprocation of the cutter, its ends will always lie within the ends of the guard. The cutter has transversely extending slots 11 arranged on opposite sides of a median bar 12. The slots are preferably one sixteenth of an inch wide and the median bar 12 is preferably about ten thousandths of an inch in width. The slots 11 are separated

by traversely extending bars 13 which are preferably one sixty-fourth of an inch in width. The slots 11 extend on opposite sides from the median bar 12 through an arc of substantially 90°. The cutter C has a hair-receiving channel or bore 14 that communicates with the cutter slots. The slots 11 are wider than the bars 13 in order to allow for a sufficient time interval for the hairs to enter the slots during each cycle or stroke of the cutter. The bore 14 is eccentrically arranged with respect to the cutter axis for providing a thin wall about ten thousandths of an inch in thickness adjacent to the median bar 12 and the inner ends of the slots 11. The cutter bars 13 quickly increase in thickness due to the difference in curvatures between the outer surface of the cutter and the inner surface of the bore 14. The inner edges 11a of the slots 11 and the parallel edges 11b constitute hair cutting edges. Although the continuity of the cutting edges 11a is broken by the interposing bars 13, these separated edges actually present continuous cutting edges while the cutter is in motion because of the end to end movement of the cutter.

The cutter C has a recess 15 in its base of the exact diameter of the roller and that receives the upper portion of the spherical roller 3. Since the spherical roller is eccentrically mounted with respect to the shaft 1, a rotation of the shaft will cause the spherical roller to move the cutter through a double helical motion. The advantage of such a motion will be presently set forth. The diameter of the recess 15 is the same as that of the spherical roller periphery.

I provide novel means for yieldingly urging the cutter toward the perforated portion of the guard. Spring-pressed balls 16 are mounted in bores 17 and bear against the cutter base. Screw plugs 18 close the lower ends of the bores and hold the springs 19 against the balls. The bores extend radially from the axis of the cutter receiving bore 6 and two bores are disposed near each end of the guard. Figure 3 illustrates the bores as extending inwardly from the base corners. The bores fall short of completely passing into the cutter receiving bore so that the inner ends of the bores will be reduced for preventing the balls 16 from entirely moving into the cutter bore should the cutter be removed and yet the balls are free to ride on the cutter to yieldingly keep the cutter in contact with the guard and to impart an inward and upward pressure to the guard. Any side slap that may have a tendency to develop due to the side thrust of the eccentric drive on the cutter base is prevented.

From the foregoing description of the various parts of the device, the operation thereof may be readily understood.

In Figure 5, I illustrate what takes place between the cutter and a circular guard opening when the cutter is moved through a complete cycle. Only one opening 7 is illustrated for purpose of clarity and four positions of the cutter C are illustrated. The eccentric stem 2 and spherical roller are assumed to be moving in a clockwise direction and in the left hand sketch of Figure 5, the cutter is being moved substantially to the left as indicated by the arrow a. Hairs received in the left portion of the opening 7 will be trapped by the cutting edge 11b and severed. The left hand portion of the cutting edge of the opening 7 is used.

Through the next 90° of swing of the eccentric, the cutter will be moved substantially laterally in the direction of the arrow b shown in the

second sketch of Figure 5. Here the cutting edge 11a of the median bar 12 comes into action and cooperates with a portion of the circular opening cutting edge 7 which is removed about 90° from the former cutting edge. Then for the next 90° of rotation of the eccentric, the cutter is moved substantially to the right as shown by the arrow c in the third sketch in Figure 5. Here the right hand edge portion of the circular opening 7 is used and the edge 11b of one of the slots 11 disposed on the opposite side of the median bar 12 comes into play. The median bar 12 has crossed the opening 7.

Finally, the last 90° of eccentric pin movement before the cycle is completed, the cutter will be moving in a substantially transverse direction as shown by the arrow d in the fourth sketch of Figure 5. The opposite side 11a of the median bar cooperates with a portion of the circular opening 7 to sever the hair therein. It will be seen that for each cycle of a double helical movement of the cutter C, four distinct portions of each circular opening 7 will be used which means that the cutter will sever hair when moving in four different general arc-like directions, each being at an angle of 90° apart from the preceding movement. The four sketches in Figure 5 give a progressive view of four general phases of one complete cycle. Hairs are sheared off on all portions of each circular opening 7.

While only four phases of the cycle or stroke of the cutter are shown, it will be noted that the peripheries of the openings 7 are engaged from all angles by the shearing edges 11a and 11b of the cutter in the course of each cycle of the cutter in its double helical motion. The straight edge of the cutter working against the concave edge of the opening 7 will create a better hair severing action than where two straight hair-cutting edges cooperate. The cutter is reciprocated from end to end and is rocked from side to side in a compound motion so that all portions of the circular openings will be used for severing hair. The cutter makes a circular cut due to its double helical movement.

The longer hairs are combed into the slots 8 by the multiple combs 9 and are kept continually combed into the guard slots by one tooth following another until the hair is severed by the cutter. The rocking of the cutter is preferably through an angle that will carry the median cutter bar 12 past the two side rows of circular openings. The end to end movement of the cutter in effect causes the two rows of spaced cutting edges 11a to become two continuous rows of cutting edges or two continuous cutting edges, one being disposed on each side of the bar 12. The outer surface of the cutter is longitudinally grooved at two places 20 on opposite sides of the bar 12. The grooves are concave in cross section and are for the purpose of reducing friction caused by the lateral stroke of the eccentric drive.

I claim:

1. An electric dry shaver comprising a guard having a plurality of circular openings therein for receiving hair, a cutter movably mounted in the guard and having a plurality of hair-cutting edges extending at right angles to each other, said cutter being simultaneously reciprocable in a longitudinal and lateral direction for causing its cutting edges to cooperate with the entire circular edges of the guard openings for severing any hair received in the openings.

2. An electric dry shaver comprising a guard having a plurality of circular hair-receiving openings therein, a cutter movably mounted in the guard and having transversely extending slots with transversely extending cutting edges, the slots being arranged on opposite sides of a median line to define a bar that has spaced longitudinally extending cutting edges arranged along each side, said cutter being simultaneously reciprocable in a longitudinal and lateral direction for causing successive cutting edges along the bar and the transverse cutting edges of the slots to pass the circular openings and sever any hair received in the openings, the longitudinal movement of the cutter in effect making continuous cutting edges along the bar sides.

3. In an electric dry shaver, a guard having a cylindrical cutter-receiving bore therein and hair-receiving openings, a cylindrical cutter slidably mounted in the bore, and spring-pressed members carried by the guard and extending radially from the cutter axis and at different angles for exerting a radial force against the cutter for yieldingly holding it against the cylindrical perforated portion of the guard while permitting the cutter to move both longitudinally and laterally.

4. In an electric dry shaver, a guard having a plurality of transversely-extending hair-receiving openings separated from each other by transversely-extending bars, and comb-like members carried by portions of the bars for combing and guiding long hairs into the openings for cutting purposes.

5. In an electric dry shaver, a guard having a plurality of circular hair-receiving openings flanked by two groups of laterally-extending hair-receiving slots, a cutter reciprocably and rockably mounted in the guard and having longitudinal and laterally-extending cutting edges, said cutter being movable through a double helical path for causing its cutting edges to cooperate with the entire rims of the circular openings for cutting hair received in the openings in various directions and for causing the cutter edges to cooperate with the slot edges for cutting longer hair received in the slots.

6. In an electric dry shaver, a guard having a plurality of circular hair-receiving openings flanked by two groups of laterally-extending hair-receiving slots, a cutter reciprocably and rockably mounted in the guard and having longitudinal and laterally-extending cutting edges, said cutter being movable through a double helical path for causing its cutting edges to cooperate with the entire rims of the circular openings for cutting hair received in the openings in various directions and for causing the cutter edges to cooperate with the slot edges for cutting longer hair received in the slots, and comb-like means placed between the slots for combing and guiding long hair into the slots for cutting purposes.

7. In combination, a guard having a plurality of rows of circular hair-receiving openings therein, a cutter movably mounted in the guard and having a median bar with longitudinal and spaced cutting edges, the cutter being rockable for moving the bar transversely across the openings, said cutter also having transverse slots with parallel and transversely extending cutting edges, said cutter also being movable longitudinally in the guard for causing the parallel cutting edges of the slots to cut hair received in the openings, whereby the arrangement of the cutting edges in the cutter and the particular movement of the

cutter will sever hair around the entire circular edges of the openings in the guard.

8. In combination, a guard having a plurality of rows of circular hair-receiving openings therein, a cutter movably mounted in the guard and having a median bar with longitudinal and spaced cutting edges, the cutter being rockable for moving the bar transversely across the openings, said cutter also having transverse slots with parallel and transversely extending cutting edges, said cutter also being movable longitudinally in the guard for causing the parallel cutting edges of the slots to cut hair received in the openings, said guard having transverse slots cooperating with the cutter slots for severing longer hair received in the guard slots.

9. In combination, a guard having a plurality of rows of circular hair-receiving openings therein, a cutter movably mounted in the guard and having a median bar with longitudinal and spaced cutting edges, the cutter being rockable for moving the bar transversely across the openings, said cutter also having transverse slots with parallel and transversely extending cutting edges, said cutter also being movable longitudinally in the guard for causing the parallel cutting edges

of the slots to cut hair received in the openings, said guard having transverse slots cooperating with the cutter slots for severing longer hair received in the guard slots, and comb-like members carried by the guard for combing longer hair into the guard slots.

10. In an electric dry shaver, a guard having a plurality of circular hair-receiving openings, and a cutter movably mounted in the guard and having cutting edges extending in substantially longitudinal and transverse directions, the cutter being movable longitudinally and transversely so that its cutting edges will be moved to take a circular path and cooperate with the guard openings for cutting hair around the entire edges of the openings.

11. In an electric dry shaver, a guard having a plurality of slots with cutting edges, said guard having bars disposed between the slots, multiple comb members carried by the bars for parting longer hair, the successive teeth in the combs parting and guiding the longer hair into the slots and holding the longer hair in the slots until severed, and a cutter for severing the hair in the slots.

AUGUST ROMAO.
